Inventor

Alfred A. Lopsey,

United States Patent Office.

ALFRED A. TORPEY, OF CHICAGO, ILLINOIS.

Letters Patent No. 81,560, dated August 25, 1868.

IMPROVED BRICK-PRESS.

The Schedule referred to in these Letters Patent and making part of the same.

TO WHOM IT MAY CONCERN:

Be it known that I, ALFRED A. TORPEY, of Chicago, in the county of Cook, and State of Illinois, have invented a new and useful Improvement in Brick-Machines; and I do declare that the following is a true and accurate description thereof, reference being had to the accompanying drawings, and to the letters of reference marked thereon, and being a part of this specification.

Figure 1 is a side view.

Figure 2 is a longitudinal sectional view from x^2 to x^1 .

Figure 3 is a transverse sectional view from x to x .

Like letters indicate like parts in each figure.

The nature of this invention consists in constructing an apparatus for pressing brick, or manufacturing the same from the earth, the machine being automatic in its operation.

The earth, after having been properly prepared, is passed into suitable moulds, and soon as filled a plate passes over and remains above the moulds. The bottoms of the moulds are the faces of movable plungers, which may be elevated to the proper distances to press the clay or earth. Soon as pressed, the top sliding plate is removed. The plungers are then elevated even with the top of the moulds, in position for the sliding plate, in its return-motion, to move off the brick after being moulded, ready to be dried. The moulds and plates are made in duplicate, and operated in connection with each other, that one set may be filling while the other is pressing, the whole being operated by suitable cams, shafts, levers, &c., as hereinafter described.

A represents the frame of the machine. B are two parallel shafts, rotating in suitable boxes attached to the sills of the frame, and connected by gear-wheels, C, firmly secured to the outer end of the shafts B, giving motion to each other, which motion is obtained, by belt or otherwise, from any rotary power.

Cams D and E are rigidly secured upon shafts B, and are in shape to give the necessary motion to plungers H, which are secured at their lower ends to a parallel bar, said bar being provided with pallets, 2, resting upon cams D and E, raising and depressing plungers H. Cam F, firmly secured at or near the outer end of shafts B², the face of which operates against pallet 4, giving a corresponding reciprocating motion to slide-bar Q, thereby transmitting the required motion to upper slide, covering-plates J and box K, through the agency of arms P and O, wrist 5, rock-shaft N, and connecting-rods L.

The red-line tracing, in fig. 1, shows the shape of inside cams D and E.

The operation of my invention is as follows:

The prepared clay or earth is placed in box K, and motion given to wheels C and shafts B, by any convenient power. The earth, passing into the left-hand moulds, is pressed and raised up, during which operation the right-hand boxes are filled. The continued motion then removes the pressed bricks from over their respective moulds, and presses and raises up those in the opposite set, while the first are again being filled.

Wheels C, in their motion, as indicated by arrows, and in opposite position of cams D and E on shafts B, secure alternate motion of the plungers, pressing the bricks in one set while the other set is being raised from the moulds, during which operation box K and sliding plates J are at rest, the plates forming the covers or tops of the moulds while the other set are filling, after which process outside cam F operates, as before described, upon pallet 4, slide-bar Q, arms O and P, rock-shaft N, and connecting-rod L moving bricks already pressed, covering the opposite moulds, which are filled, and opening moulds, preparatory to filling of the one side, while the other is being pressed, alternately, the whole forming a convenient device for the purposes specified.

I do not claim separately any of the within-described parts; but.

What I do claim as new, and desire to secure by Letters Patent, is—

The employment or use of the cams D, E, and F, pallets 4, slide-bar Q, arms O and P, rock-shaft N, when combined with plates J, connecting-rods L, and box K, substantially as and for the purposes set forth.

Witnesses:

J. W. HOUGHTELIN,

H. S. SPRAGUE.

ALFRED A. TORPEY.
